MACHINE FOR APPLYING PRESSURE TO
SHOE BOTTOMSJohn T. Lancaster, Newton, Mass., assignor to
United Shoe Machinery Corporation, Paterson,
N. J., a corporation of New Jersey

Application June 14, 1935, Serial No. 26,629

76 Claims. (Cl. 12—36)

This invention relates to improvements in machines for use in applying pressure to shoe bottoms and is illustrated herein as embodied in a machine for cement attaching soles to shoes.

During recent years a number of different types of machines have been developed for attaching soles to shoe bottoms by cement, these machines having endless series of pressure-applying units, including inflatable pads and shoe-engaging abutments, arranged to be presented successively at operating stations where soles and shoes are mounted thereon and then to be moved intermittently in circuitous paths around the machines while the soles and shoes are under pressure. The pressure in the pads is released before they return to the operating stations so that the shoes with their soles permanently attached thereto may be removed and other soles and shoes introduced on the pads.

Objects of the present invention are to provide improved means for relatively positioning soles and shoes on the pressure-applying pads of a multiple unit machine, to provide improved mechanism for applying pressure to the soles and shoes, and to provide improved means for operating and controlling such means and mechanisms whereby the operation of the machine is simplified and accelerated.

In accordance with the foregoing, a feature of the invention comprises a single set of sole and shoe-positioning gages for relatively positioning a sole and shoe on each pad of a machine of the endless conveyor type when the pad is located at an operating station, said gages being constructed and arranged to move with the pad out of said station while the pad is being inflated to apply the sole-attaching pressure, thereby causing the sole and shoe to be maintained in proper position during the inflating operation. As illustrated, the gages are carried by arms arranged to swing about a horizontal axis from a substantially vertical position into operative position over each pad in turn and means is provided for locking the arms in such position before the gages act to position the sole and shoe relatively to each other on the pad.

In accordance with another feature of the invention novel means is provided for permitting the gages to move with each pad out of the operating station, said means including a carrier member movable on a fixed support, the carrier member being automatically returned at the proper time to the operating station so that the gages will be in position to operate on the sole and shoe mounted on the following pad. In

order to permit the gages to move with the pads out of the operating station a novel arrangement is provided for detachably connecting the means that swings the gages into operative position to the gage mechanism and further means is provided for insuring that this swinging means connects properly with the gages when the latter are returned to the operating station.

Still another feature of the invention resides in the provision of novel mechanisms for movably supporting and operating the pad inflating means and for locking said means in operative position while the pad moves out of the operating station and until the desired pressure is produced in the pad, these mechanisms comprising in part a fluid pressure nozzle operated by a treadle which simultaneously causes the power drive of the machine to start the intermittent movement of the pads, and means for automatically unlocking and returning the nozzle to inoperative position when the inflating operation is completed, thereby permitting the nozzle to be returned with the gage mechanism to the operating station. The means for unlocking the nozzle and the means for unlocking the positioning gages to permit both sets of mechanism to return to the operating station are fluid pressure controlled. Preferably, and as herein illustrated, these means are operated by the fluid pressure in the pad on which the shoe being operated upon is mounted although it is within the invention to provide fluid pressure from some other source to accomplish the same result. When the pressure in the pad on which the shoe is mounted reaches a predetermined amount the unlocking means referred to are constructed and arranged to be operated in a timed sequence that causes the gages to be released from the shoe and sole before the nozzle is released from engagement with the pad. Subsequent release of the nozzle from the pad permits both sets of mechanism to return to the operating station, this being accomplished as herein illustrated automatically by a weight constantly urging the mechanisms in a direction opposite to the direction in which the pads travel.

For operating the positioning gages the illustrated machine is provided, in accordance with a further feature of the invention, with novel mechanism including a plurality of slidably rack bars cooperating with pinions, this mechanism being carried by the arms which support the gages and consequently being movable therewith into position over the respective pads. A manually-operated lever is provided for operating the rack bars and pinions and the arrangement is

5

10

15

20

25

30

35

40

45

50

55

such that movement of said lever in one direction causes the racks or slides associated with the gages at opposite sides of the shoe to move equal amounts in opposite directions thereby 5 moving the gages equal distances toward or away from the sole and shoe. Should it be desired merely to find the sole where it has been located by an operator on the pad and then to position the shoe relatively to the sole without any substantial movement of the sole laterally of the 10 pad, further means is provided operable at the will of the operator for accomplishing this result by causing certain of the slides or rack bars to operate yieldingly on floating bearings so that 15 engagement of a set of gages with either side of the sole and shoe stops such gages and causes the opposite set of gages to move into engagement therewith before the gages act to position the sole and shoe relatively to each other on the 20 pad.

Novel means is also provided for locking the gages in operative engagement with the sole and shoe after they have positioned them on the pad, this locking means being released to permit the 25 gages to be automatically withdrawn from the sole and shoe by the fluid pressure operated means referred to above, said last-named means being constructed and arranged to release the gages from the sole and shoe first and then to 30 release the gage carrying arms so that the gages will be free to swing up to their vertical or inoperative position.

Other features of the invention comprise novel 35 mechanism for insuring that the gages mounted on the same side of the shoe will all engage the sole or shoe before any relative positioning of the sole and shoe takes place; pivotal mountings for the gages which permit them to adjust themselves automatically in accordance with the 40 shape of the portions of the sole and shoe engaged thereby; and novel means for maintaining the operating surfaces of the gages normally in positions facing the sides of the sole and shoe while permitting the gages to rotate sufficiently 45 to position themselves to the shapes of the sole and shoe.

The invention also provides novel positioning 50 gages adapted to position a shoe relatively to a sole the marginal portion of which is to extend beyond or overhang the shoe bottom a predetermined amount. As illustrated, these gages comprise fingers carried by slide members and arranged to engage the opposite sides of the sole and shoe substantially at the ends of the tip 55 line and ball line, the slides being positioned to cause the fingers to approach the shoe and sole substantially at right angles to the edge of the sole and being relatively movable to cause the gages of each set to contact with a side of the 60 shoe or sole before operating to position them relatively to each other on the pad.

The sole and shoe-engaging fingers of each 65 set of the above-mentioned gages are arranged to be moved relatively to each other after contacting with the sole and shoe to position said members so that the sole margin extends beyond the shoe bottom the required amount, this being accomplished by a rotatable disk-like member carried by the gage-supporting slide and engaging 70 projections on the fingers. Upon engagement of one of the fingers with the sole or shoe respectively, the movement of that finger stops and continued movement of the slide rotates the disk-like member to force the other finger of that pair against the member it is adapted to engage, the

arrangement being such that the gage fingers move the shoe and sole relatively to each other until the overhang or extension of the sole margin at the shoe bottom is the required amount or, in other words, until the shoe and sole are 5 centralized relatively to each other.

With the above and other objects and features in view, the invention will now be described with reference to the accompanying drawings and thereafter pointed out in the claims. 10

In the drawings,

Fig. 10 is a detail view of the work-engaging ends of one pair of the sole and shoe gages illustrated in Fig. 8. 40

The invention is illustrated herein by way of example as embodied in a cement sole-attaching machine of the endless conveyor type such, for example, as that disclosed in United States Letters Patent No. 2,005,610, granted June 18, 1935, 45 on the application of William C. Card, Jr., although in many of its aspects the invention is not limited to use in a machine of that type as distinguished from machines of the rotary turret type or the so-called Ferris wheel type. As illustrated in the patent referred to, the machine is provided with a plurality of pressure-applying devices or pad boxes mounted for intermittent movement into and out of an operating station at which a sole and shoe are mounted on each of the pads in said pad boxes to receive the pressure by which the sole is to be attached to the shoe bottom. The frame of the machine comprises upstanding members 12, 12 provided at their upper ends with endless inwardly facing 50 tracks 14, 16, which are U-shaped in cross section. The pad boxes 18 contain inflatable pads 20 for applying the sole-attaching pressure and are provided at their opposite ends with pairs of downwardly projecting arms 22 carrying rolls 24 55 adapted to enter the tracks 14, 16 and thus support the pad boxes on said tracks. The pad boxes are interconnected to form an endless conveyor by a chain 26 which passes over sprocket wheels (not shown) at the opposite ends of the frame, 60 one of these sprocket wheels being driven intermittently at the proper time by a clutch (not shown) which is thrown out of operation automatically to cause the pad boxes to be presented one by one at the operating station of the ma- 70

75

chine. In the patent referred to, the clutch mechanism is manually-operated by a bell crank lever to advance the pad boxes successively into and out of the operating station and, in the present machine, this lever may be connected in any usual or suitable manner as by a link to a treadle 28 fulcrumed on a stud 29 and arranged also to operate means for introducing fluid under pressure into the pad 20 of each pad box, as will 10 appear hereinafter, thus causing the conveyor to begin moving simultaneously with the introduction of fluid under pressure into the pad.

Each pad box 18 has extending longitudinally thereof a U-shaped bail 30 having a toe rest 32 at its inner portion for engaging the forepart of a shoe and a last-engaging abutment 34 mounted for adjustment longitudinally of the bail over the heel end of the pad by a hand screw 36. On the inner end of the bail 30 (Figs. 1 and 5) is 20 mounted a toe-engaging stop or abutment 38 which is mounted for heightwise movement in a T-shaped slot 41 (Fig. 5) formed in a plate 40 carried by a horizontal screw 42 mounted in the bail and being adjustable longitudinally 25 thereof by means of a knurled hand nut 44 provided with a series of depressions 46 into which a spring-pressed plunger 48 snaps to hold the nut against turning. The screw 42 is prevented from rotating in the bail by a double-headed key 30 50. A light spring 52, connected at one end to the abutment 38 and at the other end to a pin in the plate 40, tends normally to hold the abutment 38 at the lower limit of its heightwise movement, this limit being determined by a pin 54 35 mounted in the abutment. When a pad is in the pad box the member 38 will be maintained in engagement with the upper surface of the pad, as shown in Fig. 5.

The means for inflating the pads 20 and therefore 40 by forcing the shoes against the abutments 32, 34 to applying pressure to the sole and shoe comprises a nozzle 56 arranged for sliding movement toward and away from each pad box in a casting 58 mounted for movement longitudinally of the 45 machine and parallel to the direction of movement of the pad boxes on a supporting bar 60 bolted to the frame 12. As shown in Figs. 2 and 3, the casting 58 is provided at opposite sides with two pairs of downwardly extending arms 50 62 which straddle the bar 60 and between the upper and lower ends of which are mounted two pairs of horizontal rolls 64, 66 arranged respectively to ride on the upper and lower sides of the supporting bar 60. The arms 62 also carry 55 vertical rolls 68 for engaging respectively the inner and outer surfaces of the bar 60, this construction permitting the casting 58 to move along the bar 60 while being supported in a predetermined position relatively thereto. The nozzle 56 (Fig. 3) slides in a hole in the central portion of the casting 58 and lines up with an opening in a valve member 70 secured to the inner end of the pad box by a connecting member 71 threaded on a nipple 73 and arranged to permit 60 fluid under pressure to be introduced into and exhausted from the pad. The valve 70 has an inlet port 72 to admit fluid under pressure to the pad and an outlet port 74 for exhausting it therefrom. As illustrated, the inlet port 72 is 65 normally closed by a valve 76 seated against the opening 72 and maintained in such position by a light compression spring 78. Fluid under pressure, for example, compressed air, passes through the inlet port 72 when the valve 76 is open, 70 through a bypass 82 and enters a passage 80

leading to the chamber of the pad 20. The passage 80 is connected by small openings 84 with a lower chamber 86 at the bottom of which is located the exhaust port 74. A second valve 88, hereinafter referred to as the exhaust valve, 5 closes the port 74 and is normally maintained against the port by a compression spring 90. During the inflation of the pad the pressure in the chamber 86 presses the valve 88 against the opening 74 to seal the outlet valve and thus prevent the air from escaping. 10

Before the pads arrive at the operating station where the nozzle 56 is normally located and where the inflating operation is begun, they must be deflated to permit the shoe to be removed and a fresh sole and shoe to be mounted thereon. For this purpose each exhaust valve 88 is provided with a downwardly extending pin 92 which is arranged to ride up on a substantially horizontal cam 94 (shown in broken lines in Figs. 2 and 3) 20 bolted to a stationary portion of the frame and extending longitudinally thereof in advance of the operating station for a distance approximately equal to the space between two pad boxes. The opposite ends of the cam 94 are inclined 25 downwardly to permit the pins 92 to ride up on the high portion of the cam so that each exhaust valve 88 will be held open after it leaves the position in advance of the operating station until just before it arrives at the operating station. 30 The length of the cam 94 may be varied as conditions require to allow more or less time for the pads to be exhausted. Each valve casing 70 is provided with two upwardly extending portions 96, 98 (Figs. 2 and 3) and a strap 100 surrounds 35 the portion 96 and is secured to the pad box by screws to prevent the valve casing from turning. The projections 96, 98 are provided respectively with fluid pressure-operated plungers 102, 104 the purpose of which will be explained herein- 40 after.

The nozzle 56 is threaded on the forward end of a tube 106 and has an annular flange 108 for engaging a stationary portion of the frame and thereby limiting the sliding movement of the tube 45 in the casting 58 rearwardly or away from the valve member 70. The opening in the end of the nozzle is normally closed by a check valve 110 urged against the opening by a spring 112 and having a projection 114 extending forwardly 50 beyond the end of the nozzle and arranged to engage a short projection 116 on the inlet valve 76 so that when the nozzle is moved into operative position against the valve 70, the projections 114, 116 contact to open the valves 76, 110, thereby admitting fluid under pressure to the pad. The rear portion of the air tube 106 is threaded and is connected by an elbow 118 (Fig. 1) to a flexible tubing 120 the other end of which may 55 be connected with any suitable source of fluid 60 pressure supply.

The nozzle is moved into engagement with the inlet valve 76 by mechanism operated by the treadle 28 and arranged to force the nozzle forwardly toward the valve casing yieldingly through 65 springs, the springs operating thereafter to return the nozzle to inoperative position when the pressure in the pad reaches a predetermined amount. This mechanism comprises a spacing collar 122 adjustably mounted on the threaded 70 portion of the tube 106 and acting as a fixed abutment against which the springs referred to operate in returning the nozzle to inoperative position. Slidably mounted on the tube 106 and normally held against the collar 122 by a compres- 75

sion spring 124 (Fig. 4) is a relatively large collar 126 the opposite side portions of which are extended laterally, as shown in Fig. 2. The left-hand side of this collar carries a forwardly extending shaft 128 which is hollow for a substantial portion of its length and supports the compression spring 124 the forward end of which engages the flange 108 on the nozzle. The opposite side of the collar 126 has a recess in which is seated another compression spring 132 the forward portion of which enters a hole bored in the bracket 58 and engages the bottom of the hole.

On the under side of the collar 126 is a downwardly projecting lip 134 (Fig. 3) which is in position to be engaged by a roll 136 carried on the upper arm of a bell-crank lever 138 fulcrumed on a pin 140 threaded into a bracket 142 bolted to the frame 12. The lower arm of the bell-crank lever 138 is pivotally connected to a treadle rod 144, the lower end of which is connected to the lower arm of another bell-crank lever 146 (Figs. 1 and 2) pivoted at 148 in the frame 12, the upper arm of said lever being connected by a horizontal rod 150 to an arm 152 extending upwardly from the hub of the treadle 28 and pivoting about the axis 29. The treadle 28 is normally maintained in its upper or inoperative position against a stop screw 154 by means of a tension spring 156 connected at its upper end to an angle bar 158 bolted to the bracket 142 and at its lower end to the treadle rod 144 by a collar 160.

In the operation of the mechanism the operator depresses the treadle 28 to rotate the bell-crank lever 138 in a clockwise direction, as viewed in Fig. 1, and the roll 136, through engagement with the lip 134, slides the collar 126 along the air tube 106 to compress the spring 124 against the nozzle flange 108. This forces the nozzle 56 yieldingly into engagement with the valve casing 70, thereby bringing the projections on the valves 110, 76 together to open the valves and permit fluid under pressure to enter the pad. Movement of the collar 126 also compresses the spring 132 which is seated in the bracket 58. Accordingly, when the nozzle is released in a manner to be presently described, the spring 124 acts first to return the slide collar 126 against the spacing collar 122 without having any effect upon the position of the nozzle. The spring 132 then operates to move the tube 106 and nozzle rearwardly until the flange 108 contacts with the casting 58. Rearward movement of the nozzle permits the spring 78 to close the inlet valve and prevent the compressed air from escaping from the pad.

In order to lock the nozzle 56 in operative position after it has been moved into engagement with the valve 70 of a particular pad box, the collar 126 is provided with a forwardly extending bar 162 secured to the collar 126 by a screw 164 and provided on its upper side (Fig. 3) with rearwardly inclined teeth 166, the forward portion of the bar traveling in a slot 168 formed in the upper side of the casting 58. Above the bar 162 the casting 57 is provided with an upwardly extending cylindrical projection 170 in which is mounted for vertical sliding movement a pawl 172 having formed at its lower end a single tooth arranged to engage the inclined teeth on the bar 162. The pawl is normally maintained in a lowered position with its tooth engaging one of the teeth of the bar 162 by a compression spring 174 the upper end of which engages the end of the hole formed in the projection 170 and the lower end engaging a shoulder on the pawl. As the

nozzle 56 is moved forwardly toward the valve mechanism 70 the pawl rides over the teeth 166 and at the end of the movement engages a tooth to lock the nozzle in operative position. The nozzle remains in operative position until the pressure in the pad reaches a predetermined amount after which further mechanism is operated by the pressure in the pad to raise the pawl and permit the springs 124, 132 to return the nozzle to inoperative position.

It should be pointed out that since the nozzle is locked in operative position during the inflation of each pad and since, as stated above, the treadle 28, besides moving the nozzle into engagement with the valve mechanism also trips the clutch to start the intermittent movement of the pads, the nozzle will move out of the operating station with the pad while the inflating operation is in progress and will continue moving with the pad until released by the fluid pressure-operated mechanism referred to which operates when the required pressure is produced in the pad. Movement of the air nozzle and associated mechanism out of the operating station with the pad is permitted, of course, by the movable mounting of the casting 58 on the supporting bar 60. When the nozzle is released from the operative engagement with the pad, however, and automatically returned to inoperative position by the springs 124, 132, it is desirable to return the nozzle and associated mechanism to the operating station so that it will be in position to inflate the next pad which has now moved into said station. The return of the nozzle to the operating station is accomplished by means of a weight 176 (Fig. 1) on the end of a cord 178 which passes over a pulley 180 carried by a bracket 182 bolted to the frame 12, the cord being secured at its other end in a projection 183 formed on the lower end of one of the downwardly extending arms 62 of the casting 58 by a binding screw 184. A projection 186 at the upper portion of this arm 62 is arranged to engage the frame 12 and position the mechanism at the operating station, as shown in Fig. 2.

The illustrated machine is provided with mechanism for relatively positioning a shoe and sole on each pad when the latter is located at the operating station, this mechanism being arranged to remain in operative engagement with the shoe and sole while the pad is being inflated to apply the sole-attaching pressure to the shoe bottom. The movable casting 58 has two forwardly extending arms 188, 190 (Fig. 4) which support a horizontal shaft 192. Pinned to the opposite ends of the shaft 192, outside the arms 188, 190, are arms 194, 196 which are interconnected by mechanism later to be described and which are arranged to rotate as a unit with the shaft 192 from the upwardly extending position shown in Fig. 1 into a substantially horizontal position along each side of the pad box 18 at the operating station, this position being determined by a pair of lugs 198 formed on the opposite sides of each pad box. The arms 194, 196 carry sole and shoe-positioning gages and mechanism for moving said gages into and out of operative engagement with the sole and shoe. These arms are normally maintained in the substantially vertical position shown in Fig. 1 by means of a weight 200 carried by a rearwardly extending arm 202 formed on the hub of the arm 196. The weight 200 nearly counterbalances the weight of the arms 194, 196 and the mechanism carried thereby so that the arms can be swung upwardly to inoperative position by a relatively small amount of force exerted

thereon, this force being supplied as illustrated herein by a torsion spring 204 encircling the shaft 192 and having one end secured in the arm 190 of the casting 58 and the other end in a collar 206 fastened by a set screw 208 to the shaft 192. When the arms are lowered the spring 204 is tensioned sufficiently to provide the force necessary to return the arms to inoperative position. The vertical or inoperative position of the interconnected arms 194, 196 is determined by a lug 210 projecting laterally from the arm 196 and arranged to engage the upper surface of a projection 212 formed on the casting 58.

The gage-carrying arms 194, 196 are swung 15 downwardly into operative position over the pad at the operating station by treadle-operated mechanism (Fig. 2) comprising a treadle 214 pivoted on a transverse shaft 216 the opposite ends of which are supported in bearings 218 projecting from the frame 12. The treadle 214 operates a gear segment 220 arranged to engage 20 rack teeth 221 formed on a substantially vertical slide bar 222 mounted for sliding movement in a guideway 224 formed in the lower portion of the frame and enclosed by a cover plate 225, the slide 25 bar being normally held at the lower limit of its sliding movement so that the treadle 214 is maintained in its elevated position, as shown in Fig. 1, by a tension spring 226 secured at its upper end 30 to the slide bar and at its lower end to an angle bar 228 bolted to a stationary portion of the frame 12. The slide bar is provided with a stop screw 230 arranged to engage a lug 232 formed on the cover plate 225, thereby determining the lower 35 limit of its sliding movement.

At its upper end the slide bar 222 passes through an enclosed slot in a bracket 234 bolted to the bar 60 upon which the valve mechanism slides. The upper end of the bar 222 is provided with a laterally extending pin 236 which is arranged to enter a hole in a slide block 238 (Fig. 3) mounted in a T-shaped slot 240 formed in an arm 242 extending rearwardly at an angle of about 45° from the hub portion of the gage-carrying arm 194. The slide block 238 is provided at one side with a depression which is engaged when the block is at the outer limit of its sliding movement in the slot 240 by a detent 244 pressed toward the block by a compression spring 246 mounted in a hole in the arm 242 and secured therein by a cap screw 248. To swing or rotate the arms 194, 196 about the pivot 192 to lower them into operative position, the operator depresses the treadle 214 to rotate the shaft 216 in a counterclockwise direction, as viewed in Fig. 2, and, through the gear segment 220, to elevate the slide bar 222 and thereby rotate the arm 242 into the position shown in Fig. 3; the slide block 238 moving in the T-slot 240 during such rotation out of engagement with the detent 244 and then back again to be engaged by the detent and held in position; the detent forming means for insuring that the pin or projection 236 of the gage rotating mechanism will register and connect with the hole or opening in the slide block when the gage mechanism is released and returned with the nozzle 56 to the operating station by the weight 176.

In order that the operator will not have to keep his foot on the treadle 214 to hold the arms 194, 196 in a horizontal position while the gages are being operated and while the mechanism is moving as a unit with the pad box out of the operating station, there is provided on the arm 188 of the casting 58 a flange 250 (Figs. 3 and 4)

which extends part way around the cylindrical end portion of said arm. The hub of the swinging arm 194 is provided with an upstanding projection 252 in which is slidably mounted a spring-pressed plunger 254 the lower end of which is shaped to reduce friction and is arranged to ride on the surface of the flange 250, the plunger being pressed against the flange by a compression spring 256 bearing at one end against a shoulder on the plunger and at the other end against a cover plate 258. When the gage-carrying arms 194, 196 are in the position shown in Fig. 1 the plunger is riding on the surface of the flange 250 and when the arms are swung downwardly over the pad, as shown in Fig. 3, the plunger rides off the end of the flange and locks the arms in their downwardly rotated position. The cover plate 258 extends downwardly on the farther side of the projection 252 to close the opening in the projection and is secured in place by screws, as shown in Fig. 4. This downwardly extending portion of the cover plate is provided with a vertical slot 259 through which extends a pin 260 secured in the plunger 254 and projecting laterally beyond the projection. This pin provides means for releasing the plunger from its latched engagement with the flange 250 and thus permits the gage-supporting arms to be rotated upwardly into a substantially vertical position by the weight 200 and torsion spring 204 after the positioning gages are withdrawn from the shoe and sole. Like the pawl 172, which locks the nozzle 56 in operative engagement with the valve mechanism 79, the plunger 254 is withdrawn automatically from latched position by fluid pressure-operated mechanism later to be described, the release of the plunger occurring when the pad has been fully inflated.

The sole and shoe-positioning mechanism carried by the arms 194, 196 is best illustrated in Figs. 3, 4 and 5. As shown in Figs. 3 and 4, the arms 194, 196 carry respectively at their outer portions splined shafts 262, 264 journaled in bearings formed at the central and outer portions of the arms and provided on their upper sides with keyways 266, 268. Keyed respectively to the shafts 262, 264 by double-headed keys 270 (Fig. 7) are pinions 272, 274, the keys being held in the pinions by their headed portions so that they move along the shafts with said pinions. The pinions 272, 274 are located respectively between upstanding walls of slide members 276, 278 slidably mounted in guideways 280 formed in the upper sides of the arms 194, 196. At the upper ends of the upstanding walls of the slide members 276, 278 are housings 281, 283 provided respectively with cover plates 282, 284 and having transverse openings through which pass slide arms 286, 288 provided on their lower surfaces with rack teeth 290 (Fig. 7) which mesh with the teeth on the pinions 272, 274. The splined shafts 262, 264 are prevented from moving longitudinally of their bearings in the arms 194, 196 by collars 292, 294 pinned to the outer ends of the shafts and by pinions 296, 298 pinned to the opposite ends of the respective shafts and having hubs which engage the bearings on the arms. The pinions 296, 298 are rotated by manually-operated mechanism presently to be described to move the slide arms 286, 288 toward and away from the shoe and sole on the pad, thereby moving the positioning gages which are pivoted on the inner ends of the slide arms into and out of operative engagement with the sole and shoe. In order that the gages may be ad-

justed longitudinally of the pad to position them for operating on shoes of different sizes, the slides 276, 278 are provided at their right-hand sides, as viewed in Figs. 3 and 4, with integral 5 spools 300, 302. The forward bearings on the arms 194, 196 have lateral extensions through which are threaded relatively long screws 304, 306 provided with knurled heads whereby they may be rotated and having pinned in their inner 10 ends disks 308, 310 arranged to enter the grooves in the spools 300, 302. By this arrangement the slides 276, 278 may be adjusted in the guideways 280 longitudinally of the arms 194, 196 to position the gages to accommodate shoes of different 15 lengths.

The sole and shoe-positioning gages illustrated in Figs 3 to 6, inclusive, are constructed and arranged to position a shoe A on a last L relatively to an outsole B the periphery of which 20 coincides substantially with the shape of the shoe bottom or, in other words, a shoe the outsole of which is to have no appreciable extension or overhang relatively to the shoe bottom. The gages themselves comprise curved fingers 312, 25 314 arranged to engage the inner and outer sides of either a right or a left shoe in the vicinity of the tip line, as shown in Fig. 4, a similar gage finger 316 for engaging the side of the shoe approximately at one end of the ball line and a pair 30 of somewhat smaller fingers 318 for engaging the side of the shoe short distances either side of the opposite end of the ball line. The fingers for engaging the inner side of the shoe A shown in Fig. 4 are carried at the opposite ends of a 35 horizontal lever 320 fulcrumed on a screw 322 extending vertically through the slide arm 286 (Fig. 5) and having threaded on its lower end a spacing collar 324 and lock nut 326, the collar bearing against a friction washer 328 to prevent 40 the lever 320 from pivoting too freely about the screw 322. The gage fingers 314, 316 at the outer side of the shoe A are likewise pivoted on a horizontal lever 330 pivotally secured by a screw 332 to the inner end of the slide arm 288. The 45 construction by which the gage fingers are mounted on the ends of the horizontal levers 320, 330 is the same for each gage and accordingly, a description of the mounting of the gage 316, which is illustrated in detail in Fig. 6, will be sufficient for a proper understanding of this construction.

The lower portion of the gage finger 316 curves inwardly and is arranged to engage the sole and shoe at its extreme lower portion. The upper portion of the finger is T-shaped in cross section and is mounted for heightwise sliding movement in a retaining plate 334 provided with a slot in which the finger slides. The finger is normally urged toward the lower limit of its sliding movement by a light tension spring 336 secured at its lower end to the plate 334 by a pin 338 and at its upper end to a laterally projecting finger 340 secured by screws to the upper end of the gage 316. When the gage is swung by the supporting arm 60 196 over the pad the lower end of the gage finger contacts with the upper surface of the pad permitting the finger to slide heightwise relatively to the retaining plate against the tension of the spring 336. The retaining plate 334 has a laterally projecting ear 342 formed on its outer side whereby the plate is pivotally secured to the end of the horizontal lever 330 by a stud 344, the lower end of which is threaded to receive a retaining nut 345. The projection 342 carries an eye screw 70 75 346 through which is hooked one end of a light

tension spring 348 the other end of the spring being secured to a pin 350 mounted in a rib 352 extending away from the shoe and formed on the end of the lever 330. This construction permits the retaining plate 334 to pivot about the 5 stud 344 when the finger 316 is moved into engagement with the sole and shoe and thus permits the finger to position itself in accordance with the angle of the portion of the sole and shoe engaged thereby. When the gage is withdrawn, 10 however, and returned to inoperative position, the spring 348 centralizes the retaining member on the stud 344 and thus keeps the inner surface of the gage finger always directed toward the central portion of the pad.

As stated, the gage finger 314 and the fingers 312 and 318 are pivotally mounted respectively on the horizontal levers 330, 320 by substantially the same construction as that just described except that the two fingers 318 are supported in a 20 retaining member 354 which is wide enough to support both fingers, these fingers being maintained in positions facing the central portion of the pad by a single spring 356.

The pinions 272, 274 are rotated to move the 25 gage fingers toward and away from the shoe and sole on the pad at the operating station by mechanism carried by the arms 194, 196 and interconnecting these arms so that they swing toward and away from the pad as a unit. This 30 mechanism comprises an upper rack bar or slide 358 (Figs. 2, 3 and 4) slidably mounted in housings 360, 362 formed respectively on the arms 194 196. The slide is provided on its lower side with rack teeth 364 which are engaged by the teeth 35 of a pinion 366 mounted on a hollow shaft 367 journaled in bearings formed in a housing 368 slidably mounted on the slide 358 and normally secured against movement with, or relatively to the slide, by a link 370 (Fig. 4) mounted on a 40 guideway in the arm 194 and secured in position by a bolt 372 extending through a slot in the link to permit adjustment of the latter on the arm or, when desired, to permit the link to slide on the arm. When the link 370 is rigidly secured 45 to the arm 194 the housing 368 is stationary and causes the opposite gage fingers to move positively equal amounts in opposite directions toward and away from the shoe so that the shoe and sole will be positioned on the pad as well as being 50 positioned relatively to each other. When the link 370 is free to slide on the arm 194, the housing 368 and the pinion 366 carried thereby can move on the slide 358 when the gage mechanism is operated and this construction causes the 55 gages to be moved toward the shoe yieldingly as will hereinafter appear so that they will be stopped by engagement with either the shoe or the sole resting on the pad and thus operate first merely to find the sole and shoe where they have 60 been located by the operator on the pad and then operate to position the shoe and sole relatively to each other.

Directly under the slide 358 and in line with the pinion 366 the arms 194, 196 carry respectively 65 in suitable housings short transverse slides 374, 375, the slide 374 being provided on its upper side with teeth 376 which mesh with the pinion 366. On their lower sides the slides 374, 375 are provided respectively with rack teeth 378 and 380 70 which mesh with the pinions 296, 298 which are secured to the inner ends of the splined shafts 262, 264. The slides 358 and 375 are connected together by a block 382 so that they move together. The pinion 366 is rotated to operate 75

the slides by means of a handle 384 secured to the end of the hollow shaft 367, this shaft, as shown in Fig. 4, extending transversely of the housing 368 in a bearing 386 projecting forwardly 5 from the side thereof. Normally the handle 384 is maintained in a substantially vertical position against a stop pin 388 in the end portion of the bearing 386 by a torsion spring 390 one end of which is secured in the housing 368 and the other 10 end hooked into a projection 392 formed on the hub portion of the handle. When the handle is moved toward the right, as viewed in Fig. 2, the pinion 366 is rotated in a clockwise direction to move the upper slide 358 toward the right 15 which also moves the short slide 375 in the same direction and thus rotates the pinion 298 clockwise to move the slide arm 288 toward the center of the pad. At the same time the pinion 366 moves the short slide 374 at the right-hand side 20 of the mechanism toward the left so that the pinion 296 is rotated in a counterclockwise direction to move the slide arm 286 an equal distance toward the center of the pad. Since the space ordinarily separating the gage fingers from the 25 shoe and sole is not great a relatively small amount of movement of the handle 384 will usually bring the gage fingers against the shoe and sole and cause them to position the shoe and sole relatively to each other on the pad. When the 30 pinion 366 is rotated in an opposite or counterclockwise direction by the torsion spring 390 operating on the handle 384 the direction of movement of various slide members is reversed, thereby moving the slide arms equal amounts in opposite directions to return the gage fingers to 35 inoperative positions.

Slidably mounted in the projection 392 (Fig. 3) on the handle 384 is a pawl 394 and below the pawl on the shaft 367 is a ratchet wheel 396 secured against rotation with the shaft 367 by a pin 397 (Fig. 4) extending from the hub portion of the housing 368. The pawl 394 is urged against the ratchet wheel 396 by a compression spring 398 bearing at one end against a shoulder on the 40 pawl and at the other end against the upper wall of the projection. The pawl extends upwardly through a hole in the projection and is provided with a transverse pin 400 which is engaged by a pair of ears 402 formed on a hand-operated lever 404 pivoted on the handle 384 on a pin 406. The lever 404 has a downwardly extending portion 408 which is engaged by a horizontal pin 410 slidably mounted in the lower portion of the handle and engaged at its opposite end by the tail of a lever 412 pivoted on ears projecting forwardly from the handle. The lower end of the pivoted lever 412 is arranged to engage the head of a slide rod 414 extending through the hollow shaft 367. The opposite end of the slide rod 414 is rounded 50 and projects beyond the shaft 367, as shown in Fig. 3, so that it will be in position to be engaged by a member later to be described and to be moved forwardly in the shaft 367 by this member to rotate the lever 412 in a counterclockwise direction 55 and, through the pin 410, to rotate the hand lever 404 in an opposite direction to lift the pawl 394 out of engagement with the ratchet 396 and thus permit the torsion spring 390 automatically to return the handle to inoperative position against the stop pin 388, thereby withdrawing the gage fingers from engagement with the sole and shoe. 60

The mechanism for causing the above action to take place, for lifting the plunger 254 which locks the arms 194, 196 in operative position from behind the end of the projection 250 to permit the 65

arms to be rotated into inoperative position, and also for raising the pawl 172 away from the teeth on the slide bar 162 to permit the air nozzle to return to inoperative position is operated by fluid pressure which, as herein illustrated, is supplied by the pressure in the pad being inflated. As stated above, the projection 96 on the valve casing 70 of each pad box is provided with a plunger 102 and a compression spring 416 normally urges the plunger into its lowest position in the casing. 10 The end of the plunger extends above the projection 96 and, when the pad is located at the operating station, is in position to engage an arm 418 secured to the end of a horizontal shaft 420 (Fig. 4) by a screw 422 and arranged to be rotated 15 with the shaft by the plunger 102 when the fluid pressure in the pad reaches an amount sufficient to overcome the force of the spring 416. The shaft 420 is mounted in a bearing 424 formed on the upper side of the arm 188 of the casting 20 58 and has clamped on its opposite end another arm 426 the outer end of which is slotted to engage a pin 430 mounted transversely in the upper end of the pawl 172. Consequently, when the shaft 420 is rotated by the valve plunger 102, the 25 arm 426 will lift the pawl 172 away from engagement with the teeth on the slide bar 162 and thereby unlock the air nozzle 56 from engagement with the valve casing 70 and permit the nozzle to be returned to inoperative position by 30 the compression springs 124, 132.

The shaft 420 also carries another arm 432, best shown in Fig. 4, this arm being loosely mounted on the shaft rearwardly of the arm 418 and having a laterally extending portion arranged to be engaged by the plunger 104 in the projection 98 of the valve casing 70 when a pad box is located at the operating station. The plunger 104 is held in its lowered position by a compression spring 434 (Fig. 2) which is lighter than the 40 spring 416 which operates the plunger 102, thereby causing the plunger 104 to be operated a little sooner than the plunger 102 by the fluid pressure in the pad. The arm 432 is also provided with a rearwardly extending portion having a surface 436 thereon arranged to engage the pin 260 carried by the plunger 254 which rides on the projection or flange 250 and locks the arms 194, 196 in their forwardly rotated position. An upwardly extending portion of the arm 432 is provided with an inclined surface 438 for engaging the rounded end of the slide rod 414 which operates the lever 412 on the handle 384 and releases the pawl 394 from engagement with the ratchet wheel 396, thereby permitting the 45 gage fingers to be withdrawn automatically from operative position by the torsion spring 390. 50

In the operation of the machine briefly summarized, the operator positions a shoe and sole on the pad 20 of the pad box which is located 55 at the operating station and depresses the treadle 214 to move the gage-carrying arms from the position shown in Fig. 1 into operative position over the pad. After the arms have been automatically locked in this position by the plunger 254 the operator grasps the handle 384 and moves it toward the right, as viewed in Fig. 2, to rotate the pinions 272, 274 on the splined shafts 262, 264 through the transverse slide and pinion mechanisms described above. The gage fingers move 60 equal amounts in opposite directions toward the sole and shoe and position them on the pad relatively to each other. If one finger of either pair of the opposite sets of gages contacts with either the sole or shoe before the other gage of that 65 70 75

pair, the horizontal levers 320, 330 pivot about their axes to cause the other fingers to be moved into contact with the sole or shoe by continued movement of the slide arms 286, 288 before the 5 positioning movement takes place. The gage fingers, of course, position themselves in accordance with the angles of the portions of the sole or shoe engaged thereby through their pivotal mounting on the ends of the arms 320, 330. The 10 fingers which first engage a side of the sole or shoe then move the member they engage transversely of the pad until the opposite fingers are engaging such member. When the handle 384 has forced all the fingers into engagement with 15 both the sole and shoe the latter are positioned transversely of the pad and are also centralized relatively to each other.

The operator then releases the handle 384 and the pawl 394 engages the ratchet wheel 396 to 20 lock the gages in operative position. He next depresses the treadle 28 to move the nozzle 56 into operative engagement with the valve mechanism 70, the nozzle being locked in this position by engagement of the pawl 172 with the teeth of the 25 slide bar 162, thereby causing fluid under pressure to flow into the pad 20 without further attention on the part of the operator. In depressing the treadle 28 the operator also trips the clutch which causes the pads to move intermittently into and out of the operating station so 30 that the pad upon which the sole and shoe have now been located and which is applying pressure thereto immediately starts to move out of the operating station. Since the positioning gages 35 are locked in operative position and the nozzle 56 is locked in operative engagement with the valve mechanism, both mechanisms will move as a unit with the pad as it leaves the operating station, this movement being permitted by the 40 movable mounting of the casting 58 on the supporting bar 60.

When the required fluid under pressure has been introduced into the pad so that the sole and shoe are under full pressure, the pressure in 45 the passage 80 and in the opening below the plunger 104 forces the plunger upwardly against its compression spring to cause the arm 432 to release the gage operating handle 384 thus relieving pressure of the gages against the shoe and to lift the plunger 254 away from the projection 50 250, thereby permitting the gage-carrying arms 194, 196 to be swung upwardly into a vertical position by the torsion spring 204. Immediately thereafter the plunger 102, the spring of which 55 is slightly heavier than the spring which controls the plunger 104, is forced upwardly to operate the horizontal arm 426 and to lift the pawl 172 away from the teeth of the slide bar 162, thereby permitting the nozzle 56 to return under 60 the action of its springs into inoperative position. The weight 176 thereupon operates to return the gage mechanism and the plunger 56 to the operating station which position is determined by engagement of the lug 186 with the frame 12. In 65 returning to the operating station the slide block 238 (Fig. 3) is held in the upper end of the T-slot 240 by the detent 244 so that the pin 236 is in position to register with and enter the hole in the block and thereby connect the treadle-operated mechanism with the gage arms so that 70 the latter can be operated to position a sole and shoe on the next pad which is now located at the operating station. This pad was, of course, deflated while it was moving into the operating station by engagement of the projection 92 of

the outlet valve with the exhaust cam 94 so that the operator merely removes the shoe to which a sole has been attached, places another sole and shoe on the pad and then repeats the operations described above.

If it should be desired to have the positioning gages act as feelers to find the shoe and sole where they are located by the operator on the pad and then to position them relatively to each other without any substantial movement of the sole laterally of the pad, the operator loosens the bolt 372 (Fig. 4) and permits the link 370 to slide on the arm 194, thereby causing the housing 368 to float on the slide member 358 so that operation of the handle 384 will rotate the pinion 366 and through it the pinions 272, 274 until one set of gages contacts with one side of either the sole or shoe. The transverse slide which operates this set of gages will then stop and the pinion 366 will ride along the teeth of such slide 20 while moving the opposite transverse slide to operate the pinion which moves the other set of gages against the other side of the sole and shoe. The above construction, therefore, permits either the positioning of the sole and shoe transversely of the pad and relatively to each other by equal and opposite movement of the gages at each side of the shoe or, if desired, permits the gages to be operated in such a manner that they will find the sole and shoe placed on the pad by the operator and will locate the shoe and sole relatively to each other without any substantial movement thereof relatively to the pad.

Figs. 3, 9 and 10 disclose a modified form of gage mechanism for relatively positioning a shoe 35 and sole in cases where the marginal portion of the sole is to extend beyond or overhang the edge of the shoe bottom a predetermined amount around the periphery of the shoe. The gages are mounted for movement toward and away from 40 the shoe in slide members 440 (only one of which is shown in Fig. 8) arranged to be mounted under the cover plates 282, 284 in the housings 281, 283 (Fig. 4) on the gage carrying arms 194, 196, these slides having rack teeth to permit their being 45 actuated by the pinions 272, 274. Each member 440 is provided at its opposite edge faces with converging T-shaped slots 442, 443 in which are mounted respectively slides 444, 446. The inner edges of the slide members 444, 446 have teeth 447 formed thereon which are engaged by the teeth of a pinion 448 rotatably mounted on a stud 450 extending vertically through the central portion of the slide 440. Each of the slides 444, 446 carries a pair of sole and shoe-positioning gages arranged respectively to engage the edge face of a sole B', positioned longitudinally of the pad by a toe gage 38', and the side of a shoe A' mounted on the sole, the sole-positioning gages at each side of the pad being indicated 50 by the numerals 452, 454 and the shoe-positioning gages by the numerals 456, 458. Each pair of gages is slidably mounted in a groove or guideway 459 formed in the upper surface of its supporting slide and the gages are retained in the 55 guideways by cover plates 460 secured in position by screws 462. The sole and shoe-positioning gages 452, 456 at opposite sides of the shoe are arranged to engage the sole and shoe in the vicinity of the tip line and, in order that they 60 may contact the sole and shoe substantially at right angles to the portions engaged thereby, the T-slots 443 in the slides 440 are located at acute angles relatively to the slots 442, as shown in Fig. 8. The opposite pairs of sole and shoe gages 65

454, 458 are arranged to engage the sole and shoe substantially at the ends of the ball line and like the tip line gages are arranged to move toward and away from the shoe substantially at right angles to the surfaces engaged thereby.

The inner ends of the sole and shoe-positioning gages of each set are cylindrical in shape and have mounted vertically therein work-engaging fingers 464, 466 the lower ends of which are shaped and arranged to contact respectively with the sides of the sole and shoe. The sole-engaging fingers 464 are secured in the cylindrical ends of the gages by collars 468, 470 (Figs. 8 and 10) pinned to the upper and intermediate portions of the fingers and bearing against the opposite ends of the cylindrical portions so that the sole fingers are fixed heightwise in the gages. The shoe-engaging fingers 466 are adjustable heightwise in their bearings by means of split collars 472 threaded on the stems of the fingers and clamped in position by screws 474. The holes in the cylindrical ends of the shoe gages are larger than the shank portions of the fingers 466 and compression springs 476 are provided in the holes for maintaining the shoe-engaging fingers at the lower limits of their heightwise adjustments as determined by the collars 472, the lower ends of the springs bearing against shoulders formed on the fingers. In this way each shoe-engaging finger can be adjusted until it will clear the upper edge of the sole being operated on.

The work-engaging surfaces of the gage fingers are maintained substantially in an inwardly facing position so that they will engage the sole and shoe at the proper angles by set screws 478 bearing against small friction plugs 480 (Fig. 10) which are forced against the shank portions of the fingers and create sufficient friction to prevent the fingers from turning too far in their bearings, thereby holding the fingers substantially in inwardly facing positions while permitting them to rotate sufficiently upon engagement with the sole and shoe to conform themselves to the angles of the portions engaged thereby.

The sliding portions of each pair of gages extend outwardly beyond the slide members 444, 446 in which they are mounted and have formed in their adjacent edge faces semi-cylindrical openings which register to form holes 482. Loosely mounted in each hole 482 is a plug 484 (Fig. 8), a compression spring 486, and another plug 488 which bears normally against a pair of transverse pins 490, 492 mounted respectively in the outer portions of each pair of gages, the adjacent ends of the pins extending into the holes 482. Forwardly of the hole 482 the gages of each pair are provided with upwardly extending pins 494, 496 arranged to enter radially extending slots 498, 500 formed in the opposite sides of a disk 502 having an upwardly extending stem 504 which enters a hole in the cover plate 460 and holds the disk in position on the gages while permitting it to rotate relatively thereto.

Normally the gages of each set are held with their opposite ends in substantial alinement and with the transverse slots in the disk 502 parallel to the ends of the gages by means of the compression spring 486 which forces the plug 484 against the bottom of the hole 482 and forces the plug 488 against the pins 490, 492, thereby alining the pins with each other.

As the gages at opposite sides of the shoe are moved by the slide members 440 toward the shoe it is obvious that a finger of one pair may contact with either the sole or the shoe before a

finger of the other pair at the same side of the shoe. In other words, one of the gages at the ball line may contact before one of the gages at the tip line, or vice versa. When this happens the pinion 448 will be caused by continued movement of the slide 440 to rotate in a direction to move the slide carrying the pair of gage fingers which have not yet contacted with the sole or shoe forwardly until one or the other of said gage fingers contacts with either the sole or shoe. In this way at least one gage of each set at the same side of the shoe is brought into engagement with the sole or shoe before any relative positioning movement takes place. As the gages of each pair are moved further inwardly toward the shoe by continued movement of the slide 440, the vertical pin carried by the contacting gage will move rearwardly relatively to the forwardly moving slide, thereby rotating the disk 502 in a direction to cause the opposite gage of that pair to be moved by its pin inwardly against the sole or shoe as the case may be. The construction of the mechanism is such that when one of the gages of each of the four pairs has contacted with either the sole or shoe the rotation of the disk 502 associated with that pair moves the other gage a predetermined amount to position the shoe on the sole so that the sole margin has the proper overhang or extension relatively to the shoe bottom. As the gages move away from the sole and shoe the compression springs 486 return the gages of each pair to their alined position and rotate the disks 502 so that the oppositely disposed radial slots are again substantially parallel to the ends of the gages.

By this construction any shoe operated on will be positioned relatively to its sole in such a manner that the extension of the margin of the sole relatively to the periphery of the shoe bottom will be substantially the same at each side of the shoe. Moreover, by changing the relative lengths of the sliding portions of the gages or the shapes of the fingers the extension or overhang of the sole can be made greater or smaller, as desired, or the width of the extension can be varied at different portions of the forepart of the shoe.

Having described my invention, what I claim as new and desire to secure by Letters Patent of the United States is:

1. A machine for applying pressure to shoe bottoms having, in combination, a plurality of pads arranged each to receive a sole and shoe, shoe-engaging abutments for each pad, mechanism for moving the pads successively into and out of an operating station, means movable with each pad for relatively positioning a sole and shoe thereon, and means for relatively moving the abutments and pad heightwise of the shoe to apply pressure to the shoe bottom.

2. A machine for applying pressure to shoe bottoms having, in combination, a plurality of pads arranged each to receive a sole and shoe, shoe-engaging means for each pad, mechanism for moving the pads successively into and out of an operating station, means movable out of the operating station with each pad in turn for relatively positioning a sole and shoe thereon, and means for inflating the pads to apply pressure to the soles and shoes.

3. A machine for applying pressure to shoe bottoms having, in combination, a plurality of inflatable pads arranged each to receive a sole and shoe, abutments for engaging the shoe, mechanism for moving the pads successively into and out of an operating station, means for inflating

each pad in turn while it is moving out of said operating station to apply pressure to the shoe bottom, and means for relatively positioning the sole and shoe on each pad.

5 4. A machine for applying pressure to shoe bottoms having, in combination, a plurality of pads arranged each to receive a sole and shoe, shoe-engaging abutments for each pad, mechanism for moving the pads successively into and out of an operating station, means for inflating each pad while it is moving out of the operating station to apply pressure to the shoe bottom, and means for relatively positioning the sole and shoe on each pad prior to its inflation, said means being constructed and arranged to remain in operative engagement with the sole and shoe until the pad is inflated.

10 5. A machine for applying pressure to shoe bottoms having, in combination, a plurality of inflatable pads each arranged to receive a sole and shoe, shoe-engaging abutments associated with each pad, mechanism for moving the pads one by one into and out of an operating station, means for inflating each pad in turn to apply pressure to the sole and shoe, and means at the operating station for relatively positioning the sole and shoe on each pad, said means being constructed and arranged to move out of said operating station with the pad while in operative engagement with the sole and shoe.

15 30 6. A machine for applying pressure to shoe bottoms having, in combination, a plurality of pads arranged each to receive a sole and shoe, abutments for engaging the shoe, mechanism for moving the pads successively into and out of an operating station, means movable out of the operating station with each pad in turn for relatively positioning a sole and shoe thereon, and means for inflating each pad in turn while it is moving out of the operating station thereby to apply pressure to the sole and shoe.

20 45 7. A machine for applying pressure to shoe bottoms having, in combination, a plurality of pads each arranged to apply pressure to a sole and shoe, mechanism for moving the pads successively into and out of an operating station, means movable out of the operating station with each pad in turn for relatively positioning a sole and shoe thereon, and means for returning said positioning means to the operating station after pressure has been applied to the sole and shoe.

25 50 55 8. A machine for applying pressure to shoe bottoms having, in combination, a plurality of inflatable pads each arranged to receive a sole and shoe, means for each pad for engaging the shoe, mechanism for moving the pads in turn into and out of an operating station, means for inflating each pad successively to apply pressure to the sole and shoe, means initially located at the operating station for relatively positioning the sole and shoe on each pad, said means being arranged to move with the pad out of the operating station while remaining in operative engagement with the sole and shoe, and means for returning the positioning means to said operating station.

30 60 65 70 75 9. A machine for applying pressure to shoe bottoms having, in combination, a plurality of inflatable pads each arranged to receive a sole and shoe, abutments for the shoe, mechanism for moving the pads in turn into and out of an operating station, means at the operating station for inflating each pad to apply pressure to the shoe bottom, said means completing the inflation of each pad during its movement from the oper-

ating station to a position beyond said station, and means movable out of the operating station with each pad in turn for positioning the sole and shoe relatively to each other on said pad, said means remaining in operative engagement with the sole and shoe until the pad is inflated, thereby permitting the next pad to move into the operating station while the first pad is being inflated.

- inflatable pads each arranged to receive a sole and shoe, means for locating the soles and shoes longitudinally of the pads, mechanism for moving each pad in turn into and away from an operating station, means initially located at the operating station for positioning a sole and shoe relatively to each other laterally of each pad, means at the operating station for inflating each pad in turn to apply pressure to the sole and shoe mounted thereon, said means being arranged to move away from the operating station with the pad while it is being inflated, connections between the inflating means and the positioning means for moving the latter out of the operating station with the pad so that the sole and shoe will be held in position during the inflating operation, and means for automatically withdrawing said positioning and inflating means from operative position and returning them to the operating station.
15. A machine for applying pressure to shoe bottoms having, in combination, a plurality of inflatable pads each arranged to receive a sole and shoe, mechanism for moving each pad in turn into and out of an operating station, means for positioning a sole and shoe relatively to each other on each pad when it is located at the operating station, means initially located at the operating station for inflating each pad in turn to apply pressure to the sole and shoe, said means operating while the pad moves away from the operating station, mechanism for operating said inflating means, and means for locking the positioning means in operative position before the pad moves away from said operating station, thereby causing said positioning means to move with the pad away from said station.
20. A machine for applying pressure to shoe bottoms having, in combination, a plurality of pads each arranged to receive a sole and shoe, mechanism for moving each pad in turn into and away from an operating station, an abutment for positioning the sole and shoe longitudinally of the pad, means for positioning the sole and shoe relatively to each other widthwise of the pad, means for inflating each pad in turn to apply pressure to the sole and shoe mounted thereon, mechanism for operating the inflating means, means for locking the positioning means in operative position before the pad moves away from the operating station, thereby causing said means to move away from said station with the pad, and means for releasing and returning said positioning means to the operating station after the pad has been inflated.
25. A machine for applying pressure to shoe bottoms having, in combination, a pad arranged to receive a sole and shoe, abutments for engaging the shoe, means for inflating the pad to apply pressure to the sole and shoe, means for relatively positioning the sole and shoe on the pad, means for locking said positioning means in operative position, and means operated by the pressure in the pad for releasing said locking means.
30. A machine for applying pressure to shoe bottoms having, in combination, a plurality of pads arranged each to apply pressure to a sole and shoe, mechanism for moving the pads successively into and out of an operating station, means for relatively positioning a sole and shoe on each pad, means for inflating each pad in turn to apply pressure to the sole and shoe bottom, means for locking the positioning means in operative engagement with the sole and shoe thereby causing said positioning means to hold the sole and shoe in proper position during the inflating operation, and fluid pressure operated means for releasing said locking means.
35. A machine for applying pressure to shoe bottoms having, in combination, a pad arranged to apply pressure to a sole and shoe, means for relatively positioning a sole and shoe on the pad, said means being arranged to swing from an inoperative position into operative position over the pad, means for locking said positioning means in said operative position, and fluid pressure operated means for releasing said locking means.
40. A machine for applying pressure to shoe bottoms having, in combination, a pad for applying pressure to a sole and shoe, means for relatively positioning the sole and shoe on the pad, said means being arranged to swing from an inoperative position into operative position over the pad, means for locking said positioning means in said operative position, and means controlled by the pressure in the pad for releasing said locking means.
45. A machine for applying pressure to shoe bottoms having, in combination, a plurality of pads arranged each to apply pressure to a sole and shoe, mechanism for moving the pads successively into and out of an operating station, means for relatively positioning a sole and shoe on each pad, said means being arranged to swing about a horizontal axis into operative position over each pad in turn, means for swinging said positioning means into operative position, means for locking said positioning means in such position, means operated by the fluid pressure for releasing said locking means, and means for returning said positioning means to inoperative position.
50. A machine for applying pressure to shoe bottoms having, in combination, a pad arranged to apply pressure to a sole and shoe, means for relatively positioning a sole and shoe on the pad, means for inflating the pad to apply pressure to the sole and shoe thereon, means for locking the positioning means in operative engagement with the sole and shoe, and means operated by the pressure in the pad for releasing said locking means.
55. A machine for applying pressure to shoe bottoms having, in combination, a pad arranged to receive a sole and shoe, abutments for engaging the shoe, means for inflating the pad to apply pressure to the sole and shoe mounted thereon, means for locking said inflating means in operative position, and fluid pressure controlled means for releasing said locking means.
60. A machine for applying pressure to shoe bottoms having, in combination, a pad for receiving a sole and shoe, abutments for engaging the shoe, means for inflating the pad to apply pressure to the sole and shoe, means for locking the inflating means in operative position, and means operated by the pressure in the pad for releasing said locking means.
65. A machine for applying pressure to shoe bottoms having, in combination, a plurality of pads arranged each to receive a sole and shoe, abutments for engaging the shoe, mechanism for moving the pads successively into and out of an operating station, means at the operating station for inflating each pad in turn to apply pressure to the sole and shoe thereon, means for locking said inflating means in operative position.

- tion, means controlled by the pressure in the pad for releasing said locking means, and means for returning the inflating means to inoperative position.
- 5 26. A machine for applying pressure to shoe bottoms having, in combination, a plurality of pads each arranged to receive a sole and shoe, means for engaging the shoe, mechanism for moving the pads successively into and out of an operating station, means for relatively positioning a sole and shoe on each pad, means for locking the positioning means in operative engagement with the sole and shoe, means for inflating each pad in turn to apply pressure to the sole and shoe, means for locking the inflating means in operative position, and fluid pressure controlled means for releasing both locking means.
- 10 27. A machine for applying pressure to shoe bottoms having, in combination, a plurality of pads each arranged to receive a sole and shoe, abutments on each pad for engaging the shoe, mechanism for moving the pads successively into and out of an operating station, means movable out of the operating station with each pad in turn for relatively positioning a sole and shoe on the pad, means for locking said positioning means in operative position, means for inflating each pad while it is moving out of the operating station, means for locking said inflating means in operative position, and means operated by the pressure in the pad for releasing the means for locking the positioning means and inflating means.
- 15 28. A machine for applying pressure to shoe bottoms having, in combination, a plurality of pads each arranged to receive a sole and shoe, mechanism for moving the pads successively into and out of an operating station, means for relatively positioning a sole and shoe on each pad, means for locking the positioning means in operative engagement with the sole and shoe after they have been positioned on the pad, means for inflating each pad in turn, means for locking the inflating means in operative position, and means operated by fluid pressure for releasing the means for locking the positioning means and the inflating means.
- 20 29. A machine for applying pressure to shoe bottoms having, in combination, a pad arranged to apply pressure to a sole and shoe, abutments for engaging the shoe, gages for relatively positioning a sole and shoe on the pad, means for moving the gages transversely of the pad toward the shoe to locate the sole and shoe relatively to each other on the pad, means for locking the gages in operative position after they have located the sole and shoe, means for relatively moving the abutments and pad to apply pressure to the sole and shoe, and fluid pressure controlled means for releasing the locking means.
- 25 30. A machine for applying pressure to shoe bottoms having, in combination, a plurality of pads arranged each to receive a sole and shoe, abutments for each pad for engaging the shoe, mechanism for moving the pads successively into and out of an operating station, means for relatively positioning the sole and shoe on each pad, means for locking said positioning means in operative position after the sole and shoe have been positioned on the pad, means for relatively moving the abutments and pad heightwise of the shoe to apply pressure to the shoe bottom, and fluid pressure operated means for releasing said locking means.
- 30 31. A machine for applying pressure to shoe bottoms having, in combination, a plurality of pads for applying pressure to soles and shoes, means for moving the pads successively into and out of an operating station, gages at the operating station for relatively positioning a sole and shoe on each pad, said gages being arranged to move from inoperative position into operative position over each pad in turn, means for locking the gages in said operative position, means for moving the gages toward the sole and shoe to position said members relatively to each other on the pad, means for locking the gages against the sole and shoe after they have positioned them on the pad, and fluid pressure operated means for releasing both of said locking means.
- 35 32. A machine for applying pressure to shoe bottoms having, in combination, a plurality of pads for applying pressure to soles and shoes, means for moving the pads successively into and out of an operating station, gages at the operating station for relatively positioning a sole and shoe on each pad, said gages being arranged to swing from an inoperative position into operative position over each pad in turn, means for locking said gages in said operative position, means for moving the gages toward the sole and shoe to position said members relatively to each other on the pad, means for locking the gages in engagement with the sole and shoe after they have positioned them on the pad, and means controlled by the pressure in the pad for releasing said locking means.
- 40 33. A machine for applying pressure to shoe bottoms having, in combination, a plurality of pads for applying pressure to soles and shoes, means for moving the pads successively into and out of an operating station, gages at the operating station for relatively positioning a sole and shoe on each pad, said gages being arranged to move from an inoperative position into operative position over each pad in turn, means for locking said gages in said operative position, means for moving the gages equal distances toward the sole and shoe to position said members relatively to each other on the pad, means for locking the gages against the sole and shoe after they have positioned said members on the pad, and means operated by fluid under pressure for releasing both locking means, said releasing means being constructed and arranged to release the means for locking the gages against the sole and shoe before releasing the means for locking them in operative position over the pad.
- 45 34. A machine for applying pressure to shoe bottoms having, in combination, a plurality of pads each arranged to receive a sole and shoe, abutments on each pad for engaging the shoe, mechanism for moving the pads successively into and out of an operating station, means for relatively positioning a sole and shoe on each pad in turn, said means being arranged to swing about a horizontal axis into operative position over each pad, means for swinging the gages into said operative position, means for locking the gages in such position, means for moving the gages against the sole and shoe to position them on the pad, means for locking the gages against the sole and shoe, means for inflating the pad to apply pressure to the sole and shoe, means for locking said inflating means in operative position, and fluid pressure controlled means for releasing all said locking means.
- 50 35. A machine for applying pressure to shoe bottoms having, in combination, a plurality of

- pads each arranged to receive a sole and shoe, abutments for engaging the shoe on the pads, mechanism for moving the pads successively into and out of an operating station, means for relatively positioning a sole and shoe on each pad in turn, said means being arranged to swing about a horizontal axis into operative position over each pad in turn, means for swinging the gages into said operative position, means for locking the gages in such position, means for moving the gages against the sole and shoe to position them on the pad, means for locking the gages against the sole and shoe, means for inflating the pad to apply pressure to the sole and shoe, means for locking said inflating means in operative position, and means operated by the pressure in the pad for releasing all said locking means, said releasing means operating first to release the means for locking the gages against the sole and shoe and operating thereafter to release the means for locking the gages in operative position over the pad and then to release the means for locking the inflating means in operative position.
36. A machine for applying pressure to shoe bottoms having, in combination, a plurality of inflatable pads each arranged to receive a sole and shoe, abutments associated with each pad for engaging the shoe, mechanism for moving the pads successively into and out of an operating station, means movable out of the operating station with each pad in turn for relatively positioning a sole and shoe on said pad, said means being arranged to swing from an inoperative position over the pad into operative position, means for swinging the gages into said operative position, means for locking the gages in such position, means for moving the gages equal amounts toward the sole and shoe thereby to position the sole and shoe relatively to each other on the pad, means for locking the gages against the sole and shoe after they have been positioned on the pad, means for inflating each pad in turn while it is moving out of the operating station to apply pressure to the sole and shoe thereon, means for locking the inflating means in operative position, means controlled by the fluid pressure in the pad for releasing all said locking means in timed relation to each other, and means for returning said gages and said inflating means to the operating station.
37. A machine for applying pressure to shoe bottom having, in combination, a plurality of inflatable pads each arranged to receive a sole and shoe, abutments for each pad for engaging the shoe, mechanism for moving the pads successively into and out of an operating station, a nozzle for introducing fluid under pressure into each pad in turn, means for moving the nozzle against the pad to supply fluid under pressure thereto, means for locking the nozzle in such position, thereby causing it to move with the pad out of the operating station while inflating the pad, means controlled by the pressure in the pad for releasing the nozzle from the pad, and springs for returning said nozzle to inoperative position.
38. A machine for applying pressure to shoe bottoms having, in combination, a plurality of inflatable pads each arranged to receive a sole and shoe, abutments for engaging the shoe on each pad, mechanism for moving the pads successively into and out of an operating station, means initially located at the operating station and movable in directions parallel to the move-
- ment of the pads for inflating each pad in turn to apply pressure to the shoe bottom, means for operating said inflating means while the pad is located at the operating station, means for locking said inflating means in operative position before the pad moves out of the operating station so that said inflating means will move out of said station with the pad, means actuated by fluid under pressure for releasing said locking means when the pad is fully inflated, and means for returning the inflating means to the operating station.
39. A machine for applying pressure to shoe bottoms having, in combination, a plurality of inflatable pads each arranged to receive a sole and shoe, abutments for engaging the shoe on each pad, mechanism for moving each pad in turn into and away from an operating station, gages at the operating station for relatively positioning a sole and shoe on each pad, means for inflating the pads successively as each pad moves away from the operating station to apply pressure to the shoe bottom, treadle-operated mechanism for operating said inflating means, a lock for holding said inflating means in operative position as the pad moves out of the operating station thereby causing said means to move out of said station with the pad, and connections between said inflating means and the positioning gages for causing the latter to move out of the operating station with the pad while in operative engagement with the sole and shoe, thereby causing the sole and shoe to be maintained in proper position during the inflating operation.
40. A machine for applying pressure to shoe bottoms having, in combination, a plurality of inflatable pads each arranged to receive a sole and shoe, mechanism for moving each pad in turn into and out of an operating station, gages normally located at the operating station for positioning a sole and shoe relatively to each other on each pad, means for admitting fluid under pressure to each pad in turn, said means being constructed and arranged to operate during movement of the pad from the operating station to a position beyond said station, means for operating said inflating means, means for locking said inflating means in operative position and thereby causing it to move out of the operating station with the pad, mechanism for maintaining the positioning gages in operative relation to the sole and shoe during said movement, thereby causing said gages to move out of the operating station with the pad and inflating means, and fluid pressure operated means for releasing said locking means.
41. A machine for applying pressure to shoe bottoms having, in combination, an endless carrier, a plurality of pads on the carrier each arranged to receive a sole and shoe, abutments for engaging a shoe, mechanism for moving the carrier intermittently to bring each pad in turn into and away from an operating station, gages initially located at the operating station for positioning the sole and shoe relatively to each other on each pad, means for inflating each pad, said means being constructed and arranged to inflate the pad during its movement away from the operating station, treadle-operated means for moving said inflating means into operative position, a pawl for locking said inflating means in such position and thereby causing it to move out of the operating station with the pad, and a plunger for maintaining the gages in operative

engagement with the sole and shoe prior to and during the inflation of the pad.

42. A machine for applying pressure to shoe bottoms having, in combination, an endless carrier, a plurality of inflatable pads mounted on the carrier and arranged each to receive a sole and shoe, mechanism for moving the carrier intermittently to present the pads in turn at an operating station, gages for positioning the shoe and sole relatively to each other on each pad at the operating station, a lock for maintaining said gages in operative position, means for introducing fluid under pressure to each pad in turn to inflate the pad and apply pressure to the shoe bottom, said means operating while each pad is moving from the operating station to the position beyond said station, connections between the inflating means and the positioning gages for causing the latter to move with the pad beyond the operating station while in operative relation with the shoe and sole, thereby holding the shoe and sole in proper position during inflation of the pad, spring means released by inflation of the pad for withdrawing the gages from operative position, and means for automatically returning the gages to the operating station.

43. A machine for applying pressure to shoe bottoms having, in combination, a plurality of pads arranged each to receive a sole and shoe, shoe-engaging abutments for each pad, mechanism for moving the pads successively into an operating station, means for positioning a sole and shoe on each pad, means for inflating each pad in turn to apply pressure to the sole and shoe thereon, and means for automatically retracting the positioning means when a predetermined pressure has been applied to the sole and shoe.

44. A machine for applying pressure to shoe bottoms having, in combination, a plurality of inflatable pads arranged each to receive a sole and shoe, shoe-engaging means for each pad, mechanism for moving the pads successively into an operating station, gages for relatively positioning a sole and shoe on each pad, means urging the gages normally into inoperative position, means for admitting fluid under pressure to each pad in turn to inflate it and thereby apply pressure to the shoe bottom, means for operating said gages to position the sole and shoe prior to the inflation of the pad, means for locking the gages in operative position during said inflation, and fluid-pressure-operated means for releasing said gages and permitting them to return to inoperative position when a predetermined pressure has been produced in the pad.

45. A machine for applying pressure to shoe bottoms having, in combination, a pad for receiving a sole and shoe, gage mechanism for relatively positioning the sole and shoe on the pad, said mechanism being normally located in an upwardly extending position, means for swinging the gage mechanism into operative position relatively to the surface of the pad, and means for permitting parts of said mechanism to yield heightwise of the pad thereby causing said parts to adjust themselves to the shape of said surface.

46. A machine for applying pressure to shoe bottoms having, in combination, a pad for receiving a sole and shoe, a carrier member arranged for swinging movement about an axis extending transversely of the pad, means for maintaining said member normally in an upwardly extending position, sole and shoe positioning gages carried by said member, means for

swinging the carrier member over the pad to bring the ends of the gages into engagement with the surface thereof, and springs for permitting the gages to yield heightwise of the pad to adjust themselves automatically to the shape of said surface.

47. A machine for applying pressure to shoe bottoms having, in combination, a pad for receiving a sole and shoe, a carrier member arranged for swinging movement over the pad, a spring for normally maintaining said carrier member in an inoperative position, sole and shoe gages carried by said member and arranged for sliding movement relatively thereto, springs for holding the gages at one limit of their sliding movement, and treadle-operated means for swinging the carrier member into operative position over the pad to bring the ends of the gages into contact therewith, said springs permitting the gages to slide heightwise of the pad in the carrier member and thus adjust themselves automatically to the contour of the surface of said pad.

48. A machine for applying pressure to shoe bottoms having, in combination, a plurality of pads arranged each to apply pressure to a sole and shoe, mechanism for moving the pads successively into an operating station, a carrier member, gages on said member for relatively positioning a sole and shoe on each pad in turn when it is located at the operating station, said carrier member being arranged to swing about a horizontal axis into operative position, means for normally maintaining the carrier member in an upwardly extending position, means for swinging said member into operative position, and means for locking the carrier member in said position.

49. A machine for applying pressure to shoe bottoms having, in combination, a plurality of inflatable pads arranged each to receive a sole and shoe, abutments for engaging a shoe mounted on each pad, mechanism for moving the pads successively into an operating station, means for inflating the pads in turn to apply pressure to the soles and shoes mounted thereon, gages for relatively positioning a sole and shoe on each pad, said gages being located above the pad and being arranged to swing downwardly over the pad about an axis extending transversely thereof, means including a weight for maintaining the gages in their upwardly extending position, treadle-operated means for swinging the gages into operative position, a latch for holding the gages in said operative position, and fluid pressure controlled means for releasing said latch and permitting the weight to return the gages to inoperative position.

50. A machine for applying pressure to shoe bottoms having, in combination, a plurality of inflatable pads arranged each to receive a sole and shoe, means for each pad for engaging the shoe, mechanism for moving the pads successively into and out of an operating station, means for inflating each pad in turn to apply pressure to the shoe bottom, spring means normally holding the inflating means away from the pad, treadle-operated mechanism for moving the inflating means into operative engagement with the pad, means for locking said inflating means in such position, and means actuated by the pressure in the pad for automatically releasing said locking means and thereby permitting said inflating means to be returned to inoperative position by said spring means.

51. A machine for applying pressure to shoe bottoms having, in combination, a plurality of

5 pads each arranged to receive a sole and shoe, attachments for engaging the shoe on each pad, means for moving the pads in turn into and out of an operating station, means for inflating each 5 pad to apply pressure to the sole and shoe thereon, gages for positioning the sole and shoe on each pad when it is located at the operating station, said gages being arranged to swing about a horizontal axis into operative position over the 10 pad, a spring for urging the gages normally into inoperative position and for returning them to such position after a sole and shoe have been positioned on a pad, treadle-operated mechanism for swinging the gages into operative position 15 over each pad in turn, spring-pressed means for locking the gages in operative position while the pad is being inflated, and means controlled by the pressure in the pad when it reaches a predetermined amount for automatically withdrawing 20 said spring-pressed means to unlock the gages, thereby permitting said gages to swing up to inoperative position under the influence of said spring.

52. A machine for applying pressure to shoe bottoms having, in combination, a pad for receiving a sole and shoe, gages for relatively positioning the sole and shoe on the pad, said gages comprising a slide member movable transversely of the pad and carrying fingers for engaging the 30 sole and shoe substantially at the ends of the tip line and the ball line, means for moving said slide member toward the shoe to cause the fingers to position the sole and shoe relatively to each other on the pad, and means for causing all the fingers 35 to engage either the sole or shoe before any positioning action of said fingers takes place.

53. A machine for applying pressure to shoe bottoms having, in combination, a pad for receiving a sole and shoe, and gages for relatively 40 positioning the sole and shoe on the pad, said gages comprising slide members movable equal amounts in opposite directions toward and away from the sole and shoe and provided with a plurality of fingers arranged to engage the sole and 45 shoe substantially at the ends of the tip line and the ball line, the fingers on each slide being mounted for relative swinging movement about axes located between said fingers, thereby permitting all the fingers on each slide to engage 50 either the sole or the shoe before said fingers position the sole and shoe relatively to each other on the pad.

54. A machine for applying pressure to shoe bottoms having, in combination, a pad for receiving a sole and shoe, a plurality of gages for 55 relatively positioning the sole and shoe on the pad, slide members movable transversely of the pad for supporting said gages and moving them equal amounts in opposite directions toward and away from the shoe on the pad, and levers pivoted 60 on the slide members for causing all the gages on each slide to contact with either the sole or the shoe before the relative positioning movement of said gages takes place.

55. A machine for applying pressure to shoe bottoms having, in combination, a pad for applying pressure to a sole and shoe, a plurality of gages for 65 relatively positioning the sole and shoe on the pad, said gages being arranged to engage the sole and shoe substantially at the tip line and ball line, slides for simultaneously moving the gages equal amounts toward and away from the shoe, levers pivoted on the slides for causing all 70 the gages on each slide to contact either the sole or the shoe before the positioning action of said

gages takes place, pinions for actuating said slides, means tending constantly to rotate said pinions in directions to withdraw the gages from the shoe, a pawl for preventing such rotation until the required pressure has been applied to the shoe 5 bottom, and fluid pressure controlled means for releasing said pawl.

56. A machine for applying pressure to shoe bottoms having, in combination, a pad for receiving a sole and shoe, a carrier member, levers pivoted on said carrier member, sole and shoe positioning gages pivoted on the ends of said levers, means for moving the carrier member toward the pad to bring the gages into contact therewith, and means for maintaining the work-engaging 10 surfaces of said gages yieldingly facing the sole and shoe.

57. A machine for applying pressure to shoe bottoms having, in combination, a pad for receiving a sole and shoe, a plurality of gages at opposite sides of the pad for relatively positioning the sole and shoe on the pad, mechanism for moving said gages toward the shoe, means for causing all the gages at each side of the pad to contact with either the sole or shoe before the 20 positioning action of such gages takes place, and means for permitting the gages to adjust themselves automatically to the angles of the portions of the sole and shoe engaged thereby.

58. A machine for applying pressure to shoe bottoms having, in combination, a pad for receiving a sole and shoe, a rotatable carrier member, slides on the carrier member arranged for movement toward and away from the shoe, levers fulcrumed on said slides, sole and shoe positioning 30 gages pivoted on the ends of said levers, and springs for maintaining the surfaces of the gages directed toward the sole and shoe, said springs permitting the gages to rotate sufficiently to adapt themselves to the shape of the portions of the 35 sole and shoe engaged thereby.

59. A machine for applying pressure to shoe bottoms having, in combination, a pad for receiving a sole and shoe, a rotatable member, slide arms on the rotatable member arranged for 45 movement toward and away from the shoe, levers fulcrumed on said slide arms, pivoted members on the ends of said levers having guideways formed therein, sole and shoe-positioning gages 50 slidably mounted in said guideways, springs for holding said gages normally at the lower limit of their sliding movement, means for rotating said rotatable member to bring the ends of the gages against the surface of the pad, said springs yielding to permit the gages to adjust themselves in 55 accordance with the shape of said surface, and springs for normally positioning the pivoted members so that the inner surfaces of the gages are facing the sole and shoe while allowing members to rotate sufficiently when the gages contact the 60 sole or shoe to permit the gages to align themselves with the portions of the sole and shoe engaged thereby.

60. A machine for applying pressure to shoe bottoms having, in combination, a pad for receiving a sole and shoe, a swing frame movable from an inoperative position into operative position over the pad, slides carried by said swing frame at opposite sides of the shoe, levers pivoted on said slides, gages mounted on the opposite ends 65 of said levers for positioning the sole and shoe relatively to each other on the pad, and means for adjusting said slides longitudinally of the pad to position the gages for operating upon shoes of 70 different sizes.

61. A machine for applying pressure to shoe bottoms having, in combination, a pad for receiving a sole and shoe, a swing frame movable about a horizontal axis into operative position over the 5 pad, slides carried by said swing frame at opposite sides of the shoe, gages pivoted on the slides for relatively positioning the sole and shoe on the pad, rack and pinion mechanisms for moving the slides simultaneously to bring the gages into contact with the sole and shoe, racks movable transversely of the pad for actuating said rack and pinion mechanisms, and means for moving the transverse racks simultaneously in opposite directions to operate said rack and pinion mechanisms.
- 10 62. A machine for applying pressure to shoe bottoms having, in combination, a pad for applying pressure to a sole and shoe, abutments for engaging the shoe, means for inflating the pad, gages for relatively locating the sole and shoe on the pad, means for maintaining the gages normally in inoperative position, treadle-operated mechanism for moving the gages into operative position over the pad, means including racks and pinions for moving the gages transversely of the 15 pad toward and away from the shoe, a spring for holding said racks and pinions normally in inoperative position, manually-controlled means for operating the racks and pinions to move the gages into engagement with the sole and shoe, spring-pressed means for locking the gages in operative position after they have positioned the sole and shoe, and means controlled by inflation of the pad for withdrawing said spring-pressed means and releasing the gages, thereby permitting 20 them to be retracted automatically through reverse movement of the racks and pinions under the influence of said spring.
63. In a machine for applying pressure to shoe bottoms, the combination of a pad for receiving a sole and shoe, gages for relatively positioning the sole and shoe on the pad, means for moving said gages against the sole and shoe to position them relatively to the pad, and means operable at will for causing the moving means to operate 25 the gages yieldingly to find the shoe and sole wherever they are located on the pad and thereafter to position the shoe and sole relatively to each other.
64. In a machine for applying pressure to shoe bottoms, the combination of a pad for receiving a sole and shoe, opposite sets of gages for positioning the sole and shoe relatively to each other on the pad, means for moving the gages equal amounts in opposite directions to position the 30 sole and shoe on the pad, and means operable at will for moving said gages yieldingly toward the sole and shoe to find them where they have been placed on the pad by an operator, said moving means operating thereafter to cause said gages to operate to position the sole and shoe relatively to each other.
65. In a machine for applying pressure to shoe bottoms, the combination of a pad for receiving a sole and shoe, opposite sets of sole and shoe-positioning fingers for positioning the sole and shoe relatively to each other on the pad, means for moving said fingers toward the sole and shoe to position them on the pad and then to position them relatively to each other, and means operable at the will of an operator for causing said fingers to be moved toward the sole and shoe yieldingly so that engagement of the sole-engaging fingers or the shoe-engaging fingers of either set with the sole or shoe will cause that set to 40 stop moving until the fingers of the opposite set have contacted with either the sole or shoe, said moving means operating thereafter to cause the fingers to position the shoe and sole relatively to each other on the pad.
66. In a machine for applying pressure to shoe bottoms, the combination of a pad for receiving a sole and shoe, gages for positioning the sole and shoe relatively to each other on the pad and arranged to engage the sole and shoe substantially at the ends of the tip line and ball line, slides for carrying the tip line and ball line gages, and means for causing relative movement between said slides to bring all the gages into contact with either the sole or shoe before relative positioning movement of the sole and shoe takes 45 place.
67. In a machine for applying pressure to shoe bottoms, the combination of a pad for receiving a sole and shoe, sole and shoe gages for positioning the sole and shoe relatively to each other on the pad, said gages being arranged to engage opposite sides of the sole and shoe in the vicinity of the tip line and the ball line, separate slides for carrying the tip line and the ball line gages, and means operated by engagement of either the tip line gages or the ball line gages at one side of the shoe with the sole or shoe for moving the slide carrying the other gages at that side of the shoe toward the shoe thereby bringing all the gages into contact with the sole and shoe before 50 the gages operate to position them relatively to each other on the pad.
68. In a machine for applying pressure to shoe bottoms, the combination of a pad for receiving a sole and shoe, separate sets of positioning gages arranged to engage the sides of the sole and shoe substantially at the opposite ends of the tip line and the ball line, separate slides for carrying each set of gages, means for moving the slides at each side of the shoe as a unit toward the sole and shoe, and pinions interposed between the slides at each side of the shoe and engaging teeth on the slides for causing relative movement between said slides to bring each set of gages against either the sole or shoe before the positioning action of the gages takes place, said pinions being rotated by engagement of either set of gages with the sole or the shoe and operating thereupon to move the slide carrying the other set of gages toward the shoe until at least one gage of each 55 set is contacting with either the sole or the shoe.
69. In a machine for applying pressure to shoe bottoms, the combination of a pad for receiving a sole and shoe, sole and shoe gages for relatively positioning the sole and shoe on the pad, means for moving the gages simultaneously toward the sole and shoe, and means connecting the sole gages with the shoe gages and actuated by engagement of either the sole gages or the shoe gages respectively with the sole or shoe on the 60 pad for moving the other gages amounts sufficient to position the sole and shoe relatively to each other on the pad.
70. In a machine for applying pressure to shoe bottoms, the combination of a pad for receiving a sole and shoe, a plurality of sets of sole and shoe gages for positioning the sole and shoe relatively to each other on the pad, means for moving each set of gages as a unit toward the sole and shoe, and means operated by engagement of either the sole or the shoe gage of each set with the sole or shoe for moving the other gage of said set the proper distance to position the sole relatively to the shoe.
71. In a machine for applying pressure to shoe 75

bottoms, the combination of a pad for receiving a sole and shoe, sole and shoe gages for relatively positioning the sole and shoe on the pad, means for moving the gages as a unit toward the shoe, 5 and means engaging each sole gage and shoe gage and operated by engagement of one of said gages with either the sole or the shoe for moving the other gage relatively to the contacting gage an amount effective to centralize the sole and shoe 10 relatively to each other on the pad and thus leave the proper sole extension at the shoe bottom.

72. In a machine for applying pressure to shoe bottoms, the combination of a pad for receiving a sole and shoe, pairs of sole and shoe gages for 15 relatively positioning the sole and shoe on the pad, said pairs of gages being arranged to engage opposite sides of the sole and shoe in the vicinity of the tip line and the ball line, slides for supporting said gages, means for simultaneously 20 moving said slides equal amounts toward the sole and shoe, and means for effecting predetermined relative movement between the sole and shoe gages of each pair when one or the other of said gages contacts respectively the sole or shoe, thereby 25 positioning the sole and shoe relatively to each other on the pad.

73. In a machine for applying pressure to shoe bottoms, the combination of a pad for receiving a sole and shoe, separate pairs of sole and shoe 30 gages for relatively positioning the sole and shoe on the pad, slides for supporting said gages, a disk on each slide having oppositely disposed radial slots formed therein, a projection on the sole and shoe gage of each pair entering said slots, and 35 means for moving the slides toward the shoe until either the sole or the shoe gage of each pair engages the sole or shoe and thereby rotates the disk to move the other gage a distance sufficient to centralize the sole and shoe relatively to each other on the pad.

74. In a machine for applying pressure to shoe bottoms, the combination of a pad for receiving a sole and shoe, pairs of sole and shoe gages for 40 relatively positioning the sole and shoe on the pad, said gages being arranged to engage opposite sides of the sole and shoe substantially at the tip line and the ball line, a slide for supporting each pair of gages, manually-operated means for simultaneously moving said slides toward the 45 sole and shoe, means for causing relative movement between said slides to bring at least one gage of each pair into engagement with either the sole or shoe, and means for effecting predetermined relative movement between the sole and 50 shoe gages of each pair after such engagement

and during continued movement of the slides thereby to position the shoe relatively to the sole, said means including a rotatable disk on each slide having oppositely disposed radial slots engaging a projection on each gage whereby the 5 disk is rotated by the engagement of either the sole or the shoe gage respectively with the sole or shoe, said rotation moving the gage which has not contacted with said sole or shoe an amount sufficient to bring said gage into engagement 10 therewith and then to centralize the shoe relatively to the sole.

75. A machine for applying pressure to shoe bottoms having, in combination, a plurality of 15 pads arranged each to receive a sole and shoe, mechanism for moving the pads successively into and out of an operating station, gages movable from an inoperative position to an operative position over the pad for relatively positioning a sole and shoe on each pad in turn at the operating 20 station, said gages being constructed and arranged to move out of the operating station with the pad while remaining in operative engagement with the sole and shoe, means at the operating station for rotating the gages into operative position 25 over each pad, said means being detachably connected to the gages so that the latter can move with the pad out of the operating station, and means for insuring that said rotating mechanism connects with the gages as they return to 30 the operating station.

76. A machine for applying pressure to shoe bottoms having, in combination, a plurality of pads arranged each to receive a sole and shoe, mechanism for moving the pads successively into 35 and out of an operating station, gage mechanism rotatable into operative position about a horizontal axis for relatively positioning the sole and shoe on each pad in turn at the operating station, said gage mechanism being constructed and 40 arranged to move out of the operating station with the pad while remaining in operative engagement with the sole and shoe, treadle-operated means at the operating station for rotating the gage mechanism into operative position over each pad in turn, said means having a projection thereon for engaging an opening in the gage mechanism and being arranged to disengage from 45 said opening when the gage mechanism moves out of the operating station, and means for insuring that the opening in the gage mechanism registers with said projection when said mechanism is released from the sole and shoe and returned to the operating station.

JOHN T. LANCASTER. 55
